UNITED STATES PATENT OFFICE

GORDON EDWARD ATKINSON, OF NIAGARA FALLS, NEW YORK

SIGNAL

Application filed December 15, 1928. Serial No. 326,327.

This invention pertains to improvements in signals of the lamp box type, such as are now in use on automobiles, the main object of this invention being to provide a signal of this type embodying simplification in the lamp box construction.

Other objects and advantages of the invention will become apparent to the reader after considering the invention as described and 10 claimed hereinafter.

In the drawings:—

Figure 1 represents a front elevation of the improved signal.

Fig. 2 represents a vertical sectional view 15 through the signal.

Fig. 3 represents a sectional view through the contact member of the lamp socket.

Fig. 4 represents a sectional view through the lamp socket showing a bulb in side elevation therein.

Fig. 5 represents a vertical sectional view taken substantially on the line 5—5 of Fig. 1.

Fig. 6 is a perspective view of one of the partition bodies for disposition in the signal 25 box casing.

Fig. 7 represents a vertical sectional view taken substantially on the line 7—7 of Fig. 5.

Referring to the drawings wherein like numerals designate like parts, the invention 30 includes a substantially elliptical-shaped casing 1, the same being open at one side and allotted with a lid generally referred to by the numeral 2.

This lid consists in the construction of a 35 pair of plates 3 and 4 respectively. These plates are formed at their perimeters with flanges 5 and 6 respectively for engagement over the edge portion of the casing. Coincident openings are formed in the plate, 40 and suitable complementary means between the plate serves to retain lenses 7 within the said coincidental openings.

In Fig. 7 of the drawing, a pair of partition members 8—8 are shown. These partitions are constructed of U-shaped plates secured together at their bight portions and disposed longitudinally within the casing. The legs of the respective partitions are bent laterally at their end portions to provide 50 flanges 9 for attachment to the inside of the

casing wall. In this manner, the casing is divided into a plurality of compartments.

Within each of these compartments, a 55 socket structure 10 is mounted. Each socket structure consists of a base plate 11 and a tube projecting therefrom. The tube is formed with a slot 12 to receive the usual pin 13, of a bulb 14. An insulatory body 15 is arranged within the tube and this body carries a contact for engagement with the contact 60 of the bulb. The construction of this insulatory body is more clearly shown in Fig. 3 of the drawings.

It will thus be seen that the present invention embodies a structure capable of being 65 assembled easily, and which because of this facility in assembly, will tend to lessen the cost of producing the same. It is also to be understood that slight changes in the shape, size and materials may be resorted to without departing from the spirit and scope of the 70 invention as claimed hereinafter.

Having thus described my invention, what I claim as new is:—

A lamp box comprising a casing provided 75 with a window in one side thereof, and a pair of U-shaped partitions mounted within the casing with their bight portions secured together and with their ends secured to opposite walls of the casing to divide the box into a plurality of compartments and a lamp and a lens for each of the said compartments.

In testimony whereof I affix my signature.

GORDON EDWARD ATKINSON.
